UNITED STATES PATENT OFFICE

166,828

STOCKING

Ollie A. Seay, Dallas, Tex., assignor to California Underwear Company, Inc., Dallas, Tex., a corporation of Texas

Application January 12, 1952, Serial No. 18,023

Term of patent 14 years

(Cl. D47—7)

To all whom it may concern:

Be it known that I, Ollie A. Seay, a citizen of the United States of America, residing in the city of Dallas, county of Dallas, and State of Texas, have invented a new, original, and ornamental Design for a Stocking, of which the following is a specification, reference being had to the accompanying drawing, forming part thereof.

I claim:

The ornamental design for a stocking, substantially as shown.

OLLIE A. SEAY.
